EMIL L. JOHNSON AND OLOF LUNDSTEN, OF ATTLEBORO, MASSACHUSETTS

FASTENING DEVICE FOR BRACELETS

Application filed September 24, 1930. Serial No. 434,062.

Our present invention relates to fastening devices for watch straps or bracelets and particularly pertains to the type which includes a foldable extension member attached to one bracelet section end and a cooperating adjustable element attached to the other bracelet section end.

The essential objects of our invention are to provide an extension member which has a plurality of folding sections adapted to be releasably locked together, to provide an effective and readily adjustable construction for securing the desired length of bracelet, and to form the fastening device so as to be readily adapted to the present form of open link bracelets.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a top plan view of the fastening device in closed position and forming part of an open link bracelet;

Fig. 2 is a view similar to Figure 1, but showing the fastening device in extended position;

Fig. 3 is a view similar to Figure 2, partly in section, the base of the cover being exposed to show the adjustable relationship of the parts;

Fig. 4 is a section on the line 4—4 of Figure 1;

Fig. 5 is a perspective view of the adjustable end section of the fastening device; and

Fig. 6 is a perspective view of the other end section of the fastening device.

It has been found desirable to provide a fastening device for an open link bracelet which has a plurality of foldable sections, and to provide cooperating catch and latch members on the first and last foldable sections the intermediate sections having openings to permit the releasable engagement of the catch and latch members. It has also been found advantageous to facilitate the adjust-

ment of the bracelet to the wrist by providing an end section which is attached to one bracelet section end and which has a plurality of transverse corrugations adapted to releasably receive a manually operable clamp gripping jaw in the part of the fastening device secured to the other bracelet section. Also, in order to facilitate the attachment of the fastening device to open link bracelets, both ends of the fastening device have been provided with integral sleeve portions which are adapted to pivotally engage the side posts of the contiguous open links of the bracelet sections; and the following is a detailed description of a preferred construction of fastening device which embodies the desirable features of our invention as outlined above.

Referring to the drawings, the bracelet or watch strap 10 includes a plurality of open links 11 having the usual side posts 12 which are hingedly connected together by connecting sleeves 13. An extension device 14 is shown in closed position in Figure 1, and includes a cover 15 to which are hingedly connected sections 16, 17, 18 and 19, these latter sections being hinged together and foldable within the cover section between the side walls 20 thereof as indicated in Figure 4.

An end section 21 is adjustably secured to the cover section, as shown in Figure 5, and has a plurality of corrugations 22 extending transversely thereof, these corrugations being adapted to releasably receive the gripping jaw 23 of a clamp lever 24 which is pivotally mounted as at 25 in the side walls 20 of the cover. The use of a plurality of closely spaced transverse corrugations or equivalent grooves affords an extremely simple adjustment for exactly fitting the wrist of the wearer.

As shown in Figures 2, 3 and 6, the end section 19 is provided with a latch member 26 which is preferably formed by striking up a portion of the stock and rolling it as indicated in Figure 6, and the section 16 which is hinged to the cover is provided with an opening 27 which has a catch edge or member 28 to releasably engage the latch member

26. In order to permit the releasable engagement of the cooperating catch and latch members 26 and 28, the intermediate sections 17 and 18 are respectively provided with openings 29, 30 which permit passage of the latch member therethrough to engage with the catch member, as shown in Figure 4. The elimination of any latching members from the cover portion reduces the cost of manufacture, as this cover portion is preferably made of more expensive material than the foldable sections.

18 Each end section is provided with an integral sleeve portion, as shown in Figures 5 and 6, this sleeve portion being designated as 31 for the end section 21 and as 32 for the end section 19. These integral sleeves are adapted to encircle the contiguous posts 12 of the adjacent open links 11, as shown in 20 Figure 4, thus affording a simple and effective means for attaching the fastening device to the bracelet sections. The attaching sleeves may be of any desired width so as to enable the fastening device to be fitted to 25 different styles and types of open link bracelets.

The end section 21 is preferably made as long as possible to provide ample adjustment, and is therefore provided with a central 30 opening or slot 33 so as not to interfere with the proper engagement of the cooperating latch and catch members 26 and 28.

The end section 19, which is the closing member of the fastening device, may be rectangular like the intermediate sections, or 35 may be formed as indicated in Figure 6, to impart a decorative touch.

Our improved fastening device is simple 40 to manufacture and to assemble, is sturdy in construction, permits quick and accurate adjustment of the length of the bracelet or watch strap, is easily secured to any open link type bracelet, and is releasably locked in folded position without using a latch member or the like secured to the cover.

45 While we have described certain construction forms which embody the principles of our invention, it is obvious that desired changes in arrangement, in outline, and in dimensions, may be made without departing from the spirit and the scope of the invention as defined in the appended claims.

We claim:

50 1. In an extension device for a bracelet, a cover, a manually operable clamp pivotally mounted adjacent one end of said cover and having a transverse gripping jaw, a plurality of hingedly connected sections hingedly connected to the other end of said cover and foldable upon said cover, the end section being attached to one end of the bracelet, and a second end section attached to the other end of the bracelet and slidably into said cover and provided with transverse indentations

for receiving the clamp gripping jaw of the cover.

2. In an extension device for a bracelet, a plurality of hingedly connected sections hingedly connected to one end of a cover and foldable upon said cover, the end hingedly connected section being attached to one end of the bracelet, a second end section secured to the cover and to the other end of the bracelet, a catch on the hingedly connected section adjacent said cover, and a latch on the end hingedly connected section, the intermediate hingedly connected sections having openings to permit releasable engagement of the latch and catch.

3. In a bracelet having a plurality of open links, a cover, a manually operable clamp pivotally mounted on said cover adjacent one end thereof and having a transverse gripping jaw, a plurality of hingedly connected sections hingedly connected to the other end of said cover and foldable upon said cover, the end hingedly connected section being attached to one end of the bracelet, and a second end section attached to the other end of the bracelet and slidably into said cover and provided with transverse indentations to receive the clamp gripping jaw of the cover, the end hingedly connected section and the second end section having integral attaching sleeves for lockingly receiving the contiguous posts of the bracelet links.

4. In a bracelet having a plurality of open links, a cover, a plurality of hingedly connected sections hingedly connected to one end of said cover and foldable upon said cover, the end hingedly connected section being attached to one end of the bracelet, a second end section secured to the other end of the bracelet and said cover, a catch on the hingedly connected section, directly attached to said cover, and a latch on the end hingedly connected section, the intermediate hingedly connected sections having openings to permit releasable engagement of the latch and catch, the end hingedly connected section and the second end section having integral attaching sleeves for lockingly receiving the contiguous posts of the bracelet links.

115 In testimony whereof we affix our signatures.

EMIL L. JOHNSON.
OLOF LUNDSTEN.
